UNITED STATES PATENT OFFICE.

PETER PAULSEN, OF SCHLESWIG, IOWA.

STOCK-WATERER.

1,326,778.

Specification of Letters Patent. Patented Dec. 30, 1919.

Application filed September 4, 1919. Serial No. 321,517.

To all whom it may concern:

Be it known that I, PETER PAULSEN, a citizen of the United States, residing in Schleswig, in the county of Crawford and 5 State of Iowa, have invented certain new and useful Improvements in Stock-Waterers, of which the following is a specification.

This invention relates to stock waterers in which a rotary reservoir or tank is mounted to turn about a horizontal axis within a casing which is heated to prevent water in the reservoir from freezing during freezing weather, and which delivers to a drinking trough in the lower part of the casing to 15 which access is had through suitable openings in the sides of the casing.

The object of the invention is to provide a stock waterer of this class in which the reservoir may be filled without providing a 20 special filling opening in the cover and without entirely removing the cover or lifting it to a vertical position.

A further object of the invention is to construct a stock waterer of this class in 25 such manner that the reservoir may be easily turned from feeding to filling position and vice versa without detaching the hoods or shields usually employed to protect the openings in the sides of the casing through 30 which access is had to the drinking trough. Other features of my invention will be hereinafter described.

In my U. S. Patent No. 1,312,350 of Aug. 5, 1919, I have shown a stock waterer of the 35 general kind above referred to. My present invention, however, contains a somewhat different organization of parts of the apparatus.

In the accompanying drawing:—
40 Figure 1 is a perspective view of a stock waterer embodying my invention.

Fig. 2 shows a vertical section thereof on the line 2—2 of Fig. 1.

Fig. 3 shows a vertical section on the line 45 3—3 of Fig. 1, the reservoir being in feeding position.

Fig. 4 shows a vertical section of the waterer with the reservoir in filling position.

The casing A of the waterer has a lower 50 portion a which is of general rectangular shape, and an upper portion b which is convex or semi-cylindrical. The upper portion of the casing is, however, a continuation of the lower portion and is not a separate element. It has no movement relatively there-

to, the sides of the upper and lower parts being formed of continuous pieces of metal. The upper part is, however, provided with a sliding door C which operates in guides c. The door is provided with a handle D by which it may be operated. Lamps E are placed in the lower part of the casing and these lamps may be inserted or removed through a door F provided with a latch f. G indicates a drinking trough in the lower part of the casing, and H indicates an opening through which access may be had by animals to the trough.

L indicates a cylindrical water receptacle or reservoir mounted to turn about a horizontal axis. The shaft l of the reservoir is supported by braces M which are preferably made of angle iron and which are attached to the sides of the casing in the manner indicated. These braces cross each other and the shaft l rests at the angle formed between the braces, as clearly indicated in Figs. 3 and 4 so that while the reservoir is properly supported and may be turned it can be readily lifted out of the casing or replaced 75 therein when desired. The lower ends of the cross braces M rest on horizontal braces N which also serve to support the drinking trough.

The reservoir L is filled and emptied 80 through an opening 10 in its periphery. This opening is surrounded by a hood 11, which is divided into two chambers by a partition or diaphragm 12. The inner chamber communicates directly with the reservoir 90 through the opening 10. The partition 12 is provided with an opening 14 which when the reservoir is in filling position allows water, supplied to the outer chamber to pass to the inner chamber, and thence to the 95 reservoir. The other opening is provided with a short pipe 15 which extends through the partition into the inner chamber and into the outer portion of the outer chamber. This pipe serves to transmit air passing 100 from the reservoir outward through the opening 10. It will be observed that the outer end of the pipe 15 is above any water level which might be produced in the outer chamber so that air will at all times freely 105 pass through it. The hood is closed, as clearly indicated in the drawing, and the outer wall of the hood is spaced from the periphery of the reservoir in such manner that it does not come into contact with the 110

- hood or shield H' when the reservoir is being turned from feeding to filling position or vice versa. The construction just described is similar to that shown in my 5 patent before mentioned. The reservoir is held in the filling position shown in Fig. 4 by a hook P, supported by a horizontal rod Q which is attached by nuts or burs to the sides of the casing, as indicated in Fig. 2.
- 10 The hook P engages a loop R attached to the hood 11. When the reservoir is filled the hook may be disengaged, and then the reservoir may be allowed to turn to the position shown in Fig. 3.
- 15 Further description of the construction and operation of the apparatus is unnecessary in view of the fact that many of the parts are similar to those shown in my patent above mentioned, but it should be 20 observed that in this case there is no hinged lid for the casing, a curved sliding door being employed to open and close the casing. It will be observed that the shaft of the reservoir is supported by brace rods 25 within the casing which not only serves to support the reservoir but also to stiffen and strengthen the casing. It will also be observed that the device for holding the reservoir in filling position is within convenient

reach of the attendant and may be easily 30 operated.

I claim as my invention:—

1. A stock waterer, comprising a casing having a closed back portion and side portions extending from bottom to top of the 35 casing and having curved upper ends, a curved sliding door for closing the casing at the top and at the front of the upper portion, a reservoir within the casing having its upper portion above the lower end of 40 the door, a hook-supporting rod extending across the casing in rear of the front portion of the door, and a hook supported by the rod for holding the reservoir in filling position.

2. A stock waterer, comprising a casing having a curved top, a curved sliding door in the top of the casing, a trough, horizontally arranged brace bars supporting the trough and crossed brace bars connected 50 with said horizontal bars and extending to the upper portion of the casing, a cylindrical reservoir, and a shaft for the reservoir supported by the crossed braces.

In testimony whereof, I have hereunto 55 subscribed my name.

PETER PAULSEN.
